UNITED STATES PATENT OFFICE.

JAMES A. TIPPIT, OF CARROLL'S PRAIRIE, TEXAS, ASSIGNOR OF ONE-HALF
TO GEORGE W. RANDOLPH, OF MEMPHIS, TENNESSEE.

BALE-TIE.

SPECIFICATION forming part of Letters Patent No. 314,753, dated March 31, 1885.

Application filed December 15, 1884. (No model.)

To all whom it may concern:

Be it known that I, JAMES A. TIPPIT, a citizen of the United States, residing at Carroll's Prairie, in the county of Hopkins, and State of Texas, have invented certain new and useful Improvements in Bale-Ties; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 My invention relates to improvements in bale-ties, having for its object the provision of a tie or buckle specially adapted for service in connection with a wire or rod, and one which shall be simple and durable in construction, effective in operation, and cheap of manufacture; and the invention consists of a buckle or tie consisting of a base-plate having one or more projections or hooks on its face, to one of which is permanently secured 20 one end of the wire or band, while the other end is passed around the bale and secured to the opposite hook or projection, substantially as hereinafter more fully described, and particularly pointed out in the claims.

25 In the drawings, Figure 1 is a top plan view of my improved bale-tie with the rod or wire secured thereto. Figs. 2 and 3 are side and end elevations, respectively, of the tie or buckle; and Fig. 4 is a cross-section of the 30 buckle on the line $x-x$ of Fig. 1.

35 Referring to the drawings, in which like letters of reference indicate like parts, A designates the tie or buckle, and B the band, preferably a rod or round wire, passed around 40 a bale of hay, cotton, &c., one end of which is rigidly secured, as at b, to one of the hooks or projections of the buckle, while the other end, after being passed around the bale, is formed or bent around the adjacent projection, as hereinafter described.

45 The tie or buckle A consists of a base-plate, A', preferably rectangular in shape, made in

one piece, and provided with hooks or projections a a', spaced apart longitudinally, and divided into two sets by a central transverse 50 opening, c, as shown in Figs. 1 and 2. The hooks or projections are provided with curved or rounded upper and side faces, as at c', while the inner adjacent ends of each set of hooks, which are separated by the opening c, are 55 beveled, as at d, whereby the rod or wire will closely or snugly fit the hook to which it is secured, and thereby be prevented from becoming disengaged. The plate A' is provided with longitudinal grooves e, formed therein 60 between the hooks a a', the curve of the latter meeting the lower end of the curve of the sides of the hooks a a', thereby providing a continuously-curved surface, as shown in Figs. 3 and 4, in which the rod or wire is adapted 65 to fit.

Modifications in the form and proportion of parts can be made without departing from the principle or sacrificing the advantages of my invention, the essential features of which 70 will be readily understood.

Having thus fully described my invention, what I claim as new, and desire to secure by Letters Patent, is—

1. A bale-tie consisting of a plate having 75 undercut projections or hooks in the same longitudinal plane and a rod or band, substantially as and for the purpose set forth.
2. In combination with a band or rod, a tie consisting of a base-plate having a series of 80 undercut projections or hooks spaced apart, substantially as and for the purpose set forth.
3. In a bale-tie, the combination, with a band or rod, of a tie consisting of a base-plate having a series of projections or hooks spaced 85 apart longitudinally and divided into two sets by a transverse passage, substantially as shown and described.

In testimony whereof I affix my signature in presence of two witnesses.

JAMES A. TIPPIT.

Witnesses:

J. J. MILLS,
W. A. SMITH.
